UNITED STATES PATENT OFFICE.

SYLVANUS COX AND WILLIAM W. FANNING, OF RICHMOND, INDIANA.

IMPROVEMENT IN SCHOOL-DESKS.

Specification forming part of Letters Patent No. 135,089, dated January 21, 1873.

To all whom it may concern:

Be it known that we, SYLVANUS COX and WILLIAM W. FANNING, both of Richmond, Wayne county, Indiana, have invented a new and useful School-Desk, of which the following is a specification:

Nature and Objects of the Invention.

This is an improvement in those school-desks which are supported in cast-iron frames, to which is hinged or pivoted a folding seat. The seat-frames are attached to the centers of the main frames or standards by pivot-joints, of simple and durable construction, adapted to operate without noise. The slats of which the seats are formed are secured to their arms by wood-screws, aided by projecting studs or dowels.

General Description.

Figure 1 is a perspective view of our combined school desk and seat, the latter being in the folded condition. Fig. 2 is a perspective view of the coacting parts of the pivot-joint or seat and desk coupling detached. Figs. 3 and 4 are face views of the seat coupling in the elevated and depressed conditions of the seat, respectively, the positions of the stops being indicated by dotted lines. Fig. 5 is a section of a portion of the seat-frame and connected slats.

Of the above figures the first is drawn to a smaller scale than the others.

A and A' are two corresponding castings, constituting the right and left sides, respectively, of our desk-frame. The opposing surfaces of these castings have, about their mid-height, a segmental annular groove or recess, C, concentric with the holes D, which receive the bolts E that pivot the seat-frames F F'. The extremities of the recess are dovetailed to receive and hold rubber cushions G G'. The seat-frames F F' have cast upon them bosses or disks H H' of somewhat larger diameter than the groove C, with which they are concentric; and the working-surfaces h of said bosses are flat, so as to afford a true and uniform bearing upon the main frames A A', thereby holding the seat-frames firmly in place while being shifted from the horizontal to the upright position, or vice

versa, and enabling such changes to be made with as little friction and labor as possible. Projecting from the bearing-surface h are two lugs or stops, I I', which are adapted to enter and traverse the annular groove C. Of these the stop I, preferably the larger one, is so located on the surface h as to impinge against the cushion G when the seat is lowered for use, and so as to bring the stop I', which may be of smaller size, against the other cushion, G', in the folded condition of the seat. The bosses H H' have square or other non-circular central openings h', to receive the corresponding portions e of the pivot-pins or bolts E E', as fully shown in Fig. 3. Nuts e' upon the screw-threaded extremities of the pivots E E' maintain the bosses H H' in proper contact with the main frames.

The form and location of the joint are such as to hold the seat securely in either position without the employment or necessity of any projection from the main frame, such as, in desks now in use, circumscribe the passage-way when the seats are folded for dismissal of the pupils, and are liable to catch and tear their garments.

In addition to the ordinary wood-screws J, teats or dowels K, which project from the seat-frames and enter the substance of the slats L, assist in holding the slats in position and prevent any loosening of the screws by lateral disturbance of said slats. The space between the stops I I' may be filled up, so as to constitute a single projection.

Claim.

We claim as new and of our invention—The described arrangement of seat-frames F F' having the bosses H H' and bolts E E' connecting them with the central intersecting portions of the standards A A', in the described combination with the circular grooves or cavities C and stops G G', I I', as and for the purpose set forth.

In testimony of which invention we hereunto set our hands.

SYLVANUS COX.
WILLIAM W. FANNING.
